UNITED STATES PATENT OFFICE.

D'ARCY B. PLUNKETT, OF NEW YORK, N. Y.

DESIGN FOR A FRONT MEMBER FOR RACKS OR DRAWERS.

No. 39,570.

Specification for Design.

Patented Sept. 22, 1908.

Application filed July 18, 1908. Serial No. 444,295. Term of patent 7 years.

To all whom it may concern:

Be it known that I, D'ARCY B. PLUNKETT, a subject of the King of Great Britain, residing in the city of New York, borough of Manhattan, in the county and State of New York, have invented a new, original, and ornamental Design for a Front Member for Racks or Drawers, reference is to be had to the accompanying drawing, in which the

figure is a perspective view of a front member for racks or drawers, showing my design.

I claim:

The ornamental design for a front member for racks or drawers, as shown.

D'ARCY B. PLUNKETT.
